HIS ATTORNEY

UNITED STATES PATENT OFFICE.

WILLIAM H. MINER, OF CHICAGO, ILLINOIS.

DOUBLE OR TANDEM SPRING DRAFT-RIGGING FOR RAILWAY-CARS.

SPECIFICATION forming part of Letters Patent No. 644,679, dated March 6, 1900.

Application filed March 31, 1899. Serial No. 711,234. (No model.)

To all whom it may concern:

Be it known that I, WILLIAM H. MINER, a citizen of the United States, residing in Chicago, in the county of Cook and State of Illinois, have invented a new and useful Improvement 55 in Double or Tandem Spring Draft-Rigging for Railway-Cars, of which the following is a specification.

My invention relates to improvements in 10 the construction of double or tandem spring draft-rigging for railway-cars.

The object of my invention is to improve 15 and strengthen the connection between the draw-bar and its extensions and the followers which bear against the tandem springs under either pulling or buffing strains, and thus materially add to the strength and efficiency of the draft-rigging as a whole without increasing its weight or cost.

20 My invention consists in the means I employ to accomplish this object or result—that is to say, in the novel construction of parts and devices and in the novel combinations of parts and devices herein shown and described, 25 and specified in the claims.

In the accompanying drawings, forming a part of this specification, Figure 1 is a vertical longitudinal section of a double or tandem spring draft-rigging embodying my invention. Fig. 2 is a horizontal section, and Fig. 3 is a detail perspective view, of one of the draw-bar extensions or plates.

In the drawings similar letters of reference indicate like parts in all the figures.

35 In said drawings, A A are the draft-timbers; A', the end sill; A², the buffer-plate, and A² the carrier-iron, secured by bolts to the end sill to support or guide the draw-bar C of the car-coupler.

40 B B are the draw-bar extensions, pocket-straps, or plates, secured to the rear end of the coupler draw-bar C by bolts C' C', having threaded nuts C² C² in conjunction with the flanges b at the front ends of the extension- 45 plates B, which fit in transverse grooves or gains C³ at the rear end of the draw-bar, so that the flanges or shoulders b are embraced between the front and rear shoulders C⁴ C⁵, forming the walls of said grooves or gains C³.

50 The draw-bar extension-plates B have side ribs b' b', an intermediate strengthening-rib

b², a transverse rib or offset b⁴, a rear shoulder, flange, or projection b⁵, and a transverse recess or groove b⁶ to receive the end of the intermediate spacing-block B'. The rear spacing-block B² abuts against the rear shoulder or projection b⁵ on the extension-plate.

B³ B³ are bolts inserted through the extension-plates B and the spacing or abutting blocks B' B² to secure the extension-plates together and aid in holding the spacing or abutting blocks in place against the followers F.

D D' and d d' are tandem-arranged springs, the springs D D' and d d' being preferably graduated or of different sizes, so that the 65 springs d d' may fit within the large springs D D'.

F F are followers bearing against the opposite ends of the springs, the same being furnished with central thimbles or projections f 70 to aid in holding the smaller springs in place.

G G are the draw-bar stop-castings, secured to the inner faces of the draft-timbers A A, the same having flanges or guides G' to support and guide the followers, and stops g for 75 the followers to abut against, and projections g' entering gains in the draft-timbers to aid in securing the stop-castings firmly to the draw-bars.

g² are the bolts by which the stop-castings 80 are secured to the draft-timbers.

g³ are bolts extending through the stop-castings to secure the lower guide G' thereto, the lower guide being preferably a removable one and not made integral with the stop-castings. The upper draw-bar extension-plate B is preferably provided with a socket or projection b⁸ to receive the head of the bolts B³ and prevent the same from turning.

As the spacing or abutment block B' fits at 90 its ends in the transverse recess b⁶ in the draw-bar extensions or plates B, the pressure of the followers upon the spacing-block does not have a shearing strain upon the bolt B³, and the strength and efficiency are materially 95 increased. In like manner the shoulder or flange b⁵ materially aids in holding the rear spacing or abutment block B² in place against the pressure of the rear follower, and as the front follower abuts against the rear end of 100 the draw-bar C it is also firmly held. The central rib b² of the draw-bar extension or

plate B is provided with bosses b^9 , surrounding the bolt-holes, to increase the bearing-surface of the plate against the bolts.

I claim—

- 5 1. In a tandem-spring draft-rigging for railway-cars, the combination with the draft-timbers and stop-castings, of a draw-bar, tandem-arranged springs, followers and draw-bar extensions or plates, furnished with transverse recesses, and a spacing or abutment block bearing and fitting at its ends in said transverse recesses of said draw-bar extensions or plates and bearing against the shoulders of the recesses, and a connection between said draw-bar extensions or plates substantially as specified.
- 15 2. In a tandem-spring draft-rigging, the

combination with the draft-timbers and stop-castings, of tandem -arranged springs, followers bearing against the end of the springs, 20 a draw-bar against the rear end of which the front follower abuts, a rear spacing or abutment block, and an intermediate spacing or abutment block, said draw - bar extension-plates having transverse recesses to receive 25 the ends of said intermediate spacing-block, and having shoulders at their rear ends bearing against the rear spacing-block, and connecting-bolts, substantially as specified.

WILLIAM H. MINER.
